(No Model.)

J. SMITH.

HORSE POWER.

No. 289,154.

Patented Nov. 27, 1883.

UNITED STATES PATENT OFFICE.

JOHN SMITH, OF STILLWATER, MINNESOTA.

HORSE-POWER.

SPECIFICATION forming part of Letters Patent No. 289,154, dated November 27, 1883.

Application filed April 17, 1883. (No model.)

To all whom it may concern:

Be it known that I, JOHN SMITH, a citizen of the United States, residing at Stillwater, in the county of Washington and State of Minnesota, have invented certain new and useful Improvements in Horse-Powers, of which the following is a specification, reference being had therein to the accompanying drawings.

This invention relates to certain improvements in horse-powers; and it has for its objects to dispense with the central portions of the master-wheel—*i. e.*, the hub and arms—so that a stationary platform may be arranged within the wheel, which may be occupied by an attendant, from whence he can conveniently direct and control the movement of the draft animal or animals; also to so arrange the sweeps or levers that any number may be employed.

The invention, further, has for its objects to provide certain improvements in construction in detail, as more fully hereinafter specified. These objects I attain by the means illustrated in the accompanying drawings, in which—

Figure 1 represents a plan view of my improved apparatus, and Fig. 2 a cross-section of the same, and Fig. 3 a detached sectional view of a portion of the apparatus.

The letter A indicates a rectangular frame, which supports the working parts of my apparatus, and B the master-wheel, which is in the form of an annulus having a series of internal cog-teeth, C. The said annulus is supported and adapted to travel upon anti-friction-wheels D, which are journaled upon studs projecting from the brackets E, attached to the sides of the frame. The said annulus is held down upon the friction-wheels by means of the upper friction-wheels, F, which are journaled on studs projecting from the brackets G, secured to the upper part of the frame, the said brackets in some instances being provided with horizontal cog or friction wheels H, which bear against the inner portion of the annulus. These several wheels confine the annulus and cause it to travel truly. The annulus at suitable points at its edge is

provided with brackets I and sockets K, for the reception of the sweeps or levers L, and are so arranged that the said sweeps or levers will set tangentially to its periphery, as shown, in order that as great a number as possible of such sweeps or levers may be employed, when desired.

The letter M indicates two pinions, which are mounted upon vertical shafts N, the lower ends of which are journaled in suitable bearings, P, at the lower part of the frame, the upper ends being journaled in adjustable bearings R in the brackets S, secured to the upper part of the frame, the journals being adjusted by the set-screws T to compensate for wear. The pinions intergear with the cog-teeth on the inside of the annulus, so as to impart motion to the vertical shafts when said annulus is rotated. The vertical shafts carry the beveled cog-wheels U, which intermesh with beveled pinions on the horizontal shaft V, which extends longitudinally below the master-wheel, and which is journaled in suitable bearings in the frame A. The said shaft is provided midway between its ends with a cog-wheel, A', which intermeshes with a pinion, B', through which motion is imparted by means of any suitable system of gearing, to the machinery to be driven. Instead of the cog-gearing above mentioned, a system of friction-gearing may be employed.

Having thus described my invention, what I claim, and desire to secure by Letters Patent, is—

The combination, with the rotating annulus and the anti-friction wheels upon which it travels, of the anti-friction wheels bearing upon the upper and inner edges of the master-wheel to hold it in place as it is rotated, substantially as and for the purposes specified.

In testimony whereof I affix my signature in presence of two witnesses.

JOHN SMITH.

Witnesses:

LOUIS WOLF,
JULIUS DUEL.
